BENCH REST RIFLE

Wayne E. Leek, Ilion, N. Y., assignor to Remington Arms Company, Inc., Bridgeport, Conn., a corporation of Delaware

Application March 28, 1952, Serial No. 279,006

11 Claims. (Cl. 89—37)

This invention relates to a firearm and more particularly to a firearm in which the assembly consisting of barrel, receiver, and fire control mechanism recoils freely in the stock during the time interval in which the projectile is guided by the barrel.

When the conventional firearm is fired, the assembly of barrel, receiver, and fire control mechanism is intended to recoil as a unit with the buttstock against the opposing voluntary and involuntary reactions of the shooter. It is a well-known fact that these reactions are so variable that not even two expert shooters can shoot the same arm and consistently strike a given target without adjusting the sights to compensate for their individual holding style. It is also well known that any given shooter can shoot consistently only to the extent that he has been able to train himself to consistency in every detail of the manner in which he sights, holds, and fires his arm. Further, the nature of the stresses applied by recoil is such that the fastenings securing the arm to the stock are severely strained and any shifting may drastically change the shooting characteristics of the arm.

The recently revived and currently popular sport of bench rest shooting places a premium upon extreme accuracy and matches are frequently won by differences in group size which would not be of practical significance against flesh and blood targets. Such refinements, however, are of great practical significance in the development of new arms and cartridges, particularly for long range shooting.

The principal object of my invention is the provision of an extremely accurate firearm in which the effect of the human element has been reduced to a minimum, and the principal remaining variable is that of the ammunition alone.

I have noted that the principal variable in individual shooter style seems to be the resistance with which the shooter opposes the displacement of the arm upon firing. Accordingly, I contemplate that one of the most effective means of freeing the arm from the effect of shooter reaction is to so support the arm that it will be, as nearly as possible, free in space during the time a bullet is being guided by the barrel. To that end, I propose to mount the assembly of barrel, receiver, and fire control mechanism of my improved firearm for free recoil along a line concentric with the bore during at least the time required for the bullet to pass through the barrel. I further propose to form a rigid stock in which the firearm may lay in a substantially V-block type of mounting secured almost wholly by the force of gravity acting on the firearm *per se*. In this way, the shooter may direct the line of fire but variations in his holding style can have but little effect upon the shooting characteristics of the arm.

The exact nature of the invention as well as other objects and advantages thereof will be more clearly apparent from consideration of the following specification, referring to the attached drawings in which:

Fig. 1 is a longitudinal, vertical sectional view through a firearm constructed in accordance with my invention.

2

Fig. 2 is a vertical cross-sectional view on the line 2—2 of Fig. 1.

Fig. 3 is a vertical cross-sectional view on the line 3—3 of Fig. 1.

Fig. 4 is a vertical cross-sectional view on the line 4—4 of Fig. 1.

Fig. 5 is a plan view of the buttstock unit with the assembly of barrel, receiver, and fire control mechanism removed therefrom.

10 Fig. 6 is a plan view of a bench support for such an arm. Referring to the drawings by characters of reference, it may be seen that I have provided a rifle comprising an assembly of barrel, receiver, and fire control mechanism of substantially conventional form consisting of a heavy barrel 10, receiver 11, and fire control mechanism 12. The barrel is preferably cylindrical in form rather than tapered so as to provide either a continuous bearing surface or two longitudinally spaced cylindrical bearing surfaces of like diameter and coaxial with the axis of the 15 barrel. The conventional telescope mounting blocks 13 are secured to barrel and receiver. The receiver may be of any convenient type, although I have found that the use of the mechanism described in U. S. Patent No. 2,473,373 to Howell and U. S. Patent No. 2,585,195 to 20 Walker, provides the ultimate in safety and in uniformity of the support afforded to the cartridge case. The fire control mechanism 12 also may be of any convenient type, such as that shown in U. S. Patent No. 2,514,981 to Walker and Haskell, although I prefer to use with any 25 fire control a set trigger, such as the single set trigger illustrated in the patent to Mathew H. Canjar, No. 2,556,025, June 5, 1951. The elements thus far described are not of my invention and are not therefore described in detail. For detailed drawings of these components and 30 for further description, reference may be had to the patents cited above.

The stock unit, indicated generally by the numeral 14 and shown in plan in Fig. 5, comprises a rigid frame member 15 which may conveniently be formed from a channel 40 member of a convenient structural aluminum alloy. Mounted within this channel are a pair of similar base blocks 16 and 17, each arranged to support at right angles to each other a pair of axles 18 on which rollers 19 are rotatably mounted, preferably by means of precision roller bearings, such as, for example, the bearing construction shown in Fig. 2 and illustrated in more detail in U. S. Patent No. 2,099,660. These two pairs of rollers form parallel V-ways in which the cylindrical barrel 10 may be received for lengthwise movement along its axis.

45 50 When the barrel is so received on the V-rollers, it makes a substantially point contact with each roller, thus displacing lubricants or other material which may be on either barrel or roller and assuring consistency in the line of movement. The lower portion of the channel frame 55 15 is cut away to receive the fire control mechanism 12 and the trigger thereof projects into a trigger guard 20 attached to the frame.

The rearward excursion of the assembly of barrel, receiver, and fire control mechanism is limited by a recoil 60 plate 21 engaged between a shoulder on the barrel and the forward face of the receiver or otherwise secured thereto. This recoil plate is faced with fiber 22 or other shock absorbing material and, at the rearward limit of recoil, impinges upon a member 23 secured between the side 65 walls of the frame member 15.

A block 24 depending from the barrel may be itself 70 formed of ferrous material or may be of aluminum and provided with a ferro-magnetic element 25. This element is arranged to contact the poles of a magnet 26 and thereby to provide a forward stop for movement of the barrel. The attraction of the magnet for the ferromagnetic element releasably retains the barrel in its forward

position with a force which is sufficient to retain the arm in forward position under all normal conditions and which can be relied upon to remain substantially constant. In common with other magnetic devices, once a slight separation has been made the attractive force will rapidly vanish. The forces which oppose the magnet are those of gravity when the arm is pointed slightly upward and the slight force required to pull the set trigger. Obviously, the positions of the magnet 26 and element 25 may be interchanged and in the claims the terms ferromagnetic elements exerting an attractive force upon each other are intended to include the magnet 26 and element 25 in either relative position. Obviously the magnet 26 may be either an electro-magnet or a permanent magnet, although the latter is preferred for the sake of simplicity.

It will be appreciated that with any rifled arm there will be a torque reaction resulting from the application of a spinning force to the bullet. This force is resisted by a roller 27 similar to the V-rollers and supported in the base of the frame 15 to bear on a torque resisting bearing surface which may conveniently be a cylindrical member 28 of drill rod, or the like, supported on the block 24 in parallelism with the bore of the barrel. A similar cylindrical member 29 is mounted on the opposite side of the block 24 likewise in parallelism with the axis of the barrel and defines an upwardly facing bearing surface on which a flexibly mounted roller 30 bears, urging the member 28 to follow the roller 27 and exerting a slight downward force resisting any tendency of the barrel to jump away from the V-rollers when the recoil plate is stopped.

In an exemplary embodiment of my invention I have provided for a free recoil of about one-fourth of an inch. Although it may seem that the stopping of the assembly of barrel, receiver, and fire control mechanism by the recoil plate after so short a recoil would exert a disturbing influence on the trajectory, I have found by careful timing tests that the lowest velocity projectile I have found it practicable to use is out of the barrel in one milli-second or less, which is a considerably shorter period of time than that required for the assembly of barrel, receiver, and fire control mechanism to be accelerated and to recoil for one quarter of an inch. Thus, during the time the bullet is being guided by the barrel the assembly of barrel, receiver, and fire control mechanism is substantially unopposed by any outside force. With higher bullet velocities and a heavier assembly of barrel, receiver, and fire control mechanism, a free recoil of one-eighth inch may be adequate to permit the bullet to emerge from the barrel before the barrel is stopped. I have not encountered any practical combination which seems to require more than one-half inch of free recoil. As indicated, one-quarter of an inch is a satisfactory value for most purposes.

A buttstock 31 may be formed with a metallic frame 32 attached to the frame 15 in any suitable way and the exterior surfaces of both frames 15 and 32 may be surfaced with walnut or other material shaped to the desired contours.

Although I have described above a rifle which may be used in bench rest competition in the usual manner, I have found that additional support is desirable. Accordingly, I have provided on the buttstock frame 32 a universally mounted shoe plate 32a which may bear upon the top of a shooting bench or level plate thereon and thus establish a fixed elevation level for the buttstock. On the lower surface of the forestock frame 15 I have provided a plate 33 which is parallel to the line of the bore of a barrel supported on the V-rollers and normal to a line bisecting the angle defined between the V-rollers. This plate may be supported on a pair of parallel rollers 34 mounted on a rest frame 35 which is adapted to be supported on the top of a shooting bench.

The frame 35 is preferably provided with three leveling screw feet 36 by which the frame may be leveled and have its elevation adjusted. To insure that after

each shot the arm may be returned to the same position for firing, I provide on the plate 33 a depending ball 37 which can be entered into the V-notch 38 supported in the frame 35.

In utilizing my invention, I prefer to set up on the top of a rigid, conventional shooting bench and, by a process of successive adjustments of the levelling screws 36 and telescope sight mounted on the barrel, arrive at a setting which will place the point of impact of the bullets at the intersection of the telescope cross hairs.

In shooting each shot, the ball 37 is entered into the V-notch 38 and with the assembly of barrel, receiver, and fire control mechanism in the forward position against the magnetic stop it is carefully aimed with the telescope pointing to the desired point of impact. With such alignment and at a time determined by wind and other variable factors, I may fire the rifle with the set trigger. At the instant of firing, the assembly of barrel, receiver, and fire control mechanism is restrained only by the magnet and by gravitational forces holding it down in the V-rollers. The only outside influence affecting the assembly of barrel, receiver, and fire control mechanism is the touch on the set trigger, which, if properly designed may safely be measured in ounces or fractions thereof and, in any event, should be less than the force required to displace the armature from the magnet. Upon firing, the force of recoil readily separates the armature from the magnet and the assembly of barrel, receiver, and fire control mechanism recoils freely in space, guided by the V-rollers and opposed only by inertia and the slight frictional forces of the guiding rollers. Since the assembly of barrel, receiver, and fire control mechanism is substantially symmetrical with respect to the bore axis and the only non-symmetrical members are the bolt handle, fire control assembly 12, depending block 24, and the usual loosely mounted telescope sight, there will be no significant couples resulting from inertia forces tending to disturb the straight line recoil of the barrel. The rigidity and weight of the stock unit and the manner of supporting it on the bench are such that it is substantially impossible for a shooter to disturb the position of the stock unit and, hence, that of the line of recoil in the brief interval between actuation of the set trigger and the departure of the bullet. Thus, while the bullet is being guided by the barrel, it is substantially free from human influences. After the bullet has departed from the barrel, the recoil of the assembly of barrel, receiver, and fire control mechanism will be stopped by the recoil plate and the stock unit may also be moved slightly.

Succeeding shots are fired in the same way, care being taken each time to return the stock unit to the same location on its supports, to return the assembly of barrel, receiver, and fire control mechanism to its forward position of engagement with the magnet and to re-establish conformity of the sights with the point of desired impact. By the use of this equipment and following this technique, I have found that even relatively unskilled shooters can produce results which will be competitive with those of highly skilled marksmen employing conventional equipment.

It may also be noted that a plurality of assemblies of barrel, receiver, and fire control mechanism may be used interchangeably and with equal accuracy in a single stock unit, thus minimizing the cost of full participation in the sport. Generally, rifles of about .22 caliber are employed in 100 yard competition and rifles of larger caliber are regarded as essential for the longer range contests because of their greater "wind-bucking" ability.

While I have quite specifically described herein a preferred embodiment of my invention, it should not be inferred that I consider my invention limited to that embodiment. For an exact definition of the limits upon the scope of my invention, reference may be made to the claims following.

I claim:

1. A rifle comprising the combination of an assembly including a rifled barrel, a receiver, a fire control mechanism, and longitudinally spaced cylindrical bearing surfaces coaxial with the axis of the barrel; with a stock unit provided with support means providing V-defining members engaging said bearing surfaces and supporting said assembly for straight line recoil relative to said stock unit, said V-defining members each including a pair of axles substantially axially parallel to the corresponding side of the V and a pair of substantially cylindrical rollers rotatably supported on said axles, said rollers engaging said bearing surfaces on said assembly.

2. A rifle as described in claim 1, including anti-friction bearings between each of said rollers and its corresponding axle.

3. A rifle as described in claim 2, said assembly including a ferro-magnetic element and said stock unit including another ferro-magnetic element exerting an attractive force upon said first ferro-magnetic element, the attractive force tending to releasably retain said assembly in a normal position of rest in said stock unit.

4. A rifle as described in claim 3, including a depending recoil plate on said assembly and an abutment in said stock unit in opposition to said recoil plate and in position to stop recoil of said assembly within from one-eighth to one-half an inch from said normal position.

5. A rifle as described in claim 4, said assembly being provided with a depending element having a torque resisting bearing surface axially parallel to said longitudinally spaced bearing surfaces; and resisting means on said stock unit against which the bearing surface on said element may bear to resist the torque reaction resulting from the rotation of a bullet by the rifled barrel.

6. A rifle as described in claim 5, said resisting means on said stock unit comprising a fixed axle extending substantially at a right angle to the axis of said torque resisting bearing surface and a roller rotatably mounted on said fixed axle and bearing on said torque resisting bearing surface.

7. A rifle as described in claim 6, said depending element being also provided with an upwardly facing bearing surface parallel to said torque resisting bearing sur-

face; and pressure means on said stock unit resiliently exerting a downward pressure on said upwardly facing bearing surface tending to hold said assembly in engagement with said support means in the stock unit.

5 8. A rifle as described in claim 7, said pressure means including a roller journaled on said stock unit making the actual contact with said upwardly facing bearing surface.

10 9. A rifle as described in claim 1, said assembly being provided with a torque resisting bearing surface radially displaced from the axis of the bore but parallel thereto and resisting means on said stock unit against which said torque resisting bearing surface may bear to resist the torque reaction resulting from the rotation of a bullet by the rifled barrel.

15 10. A rifle as described in claim 9, said assembly including a ferro-magnetic element and said stock unit including another ferro-magnetic element, one of said ferro-magnetic elements being permanently magnetized and positioned to exert an attractive force upon the other ferro-magnetic element tending to retain said assembly in a normal position of rest on said stock unit.

20 11. A rifle as described in claim 10, said assembly being provided with a recoil plate projecting outwardly away from the axis of said barrel and an abutment in said stock unit positioned to be engaged by said recoil plate and limit the recoil of said assembly to a distance between one-eighth and one-half an inch from said normal position of rest.

25 30 12. A rifle as described in claim 11, said assembly being provided with a depending element having a torque resisting bearing surface axially parallel to said longitudinally spaced bearing surfaces; and resisting means on said stock unit against which the bearing surface on said element may bear to resist the torque reaction resulting from the rotation of a bullet by the rifled barrel.

35 13. A rifle as described in claim 12, said depending element being also provided with an upwardly facing bearing surface parallel to said torque resisting bearing sur-
